E. DEATRICK

RELEASABLE CONNECTER

Filed April 18, 1922

Patented July 8, 1924.

UNITED STATES PATENT OFFICE.

EDWARD DEATRICK, OF LANCASTER, PENNSYLVANIA.

RELEASEABLE CONNECTER.

Application filed April 18, 1922. Serial No. 554,560.

To all whom it may concern:

Be it known that I, EDWARD DEATRICK, a citizen of the United States, residing at Lancaster, in the county of Lancaster and State of Pennsylvania, have invented certain new and useful Improvements in Releasable Connecters, of which the following is a specification.

This invention relates to releasable connectors and is useful for many purposes such as quickly releasing live stock in an emergency or at any time.

The object of the invention is to produce a simple and reliable device of the character specified, which will enable a connector member, such as the terminal link or ring of a chain, to be securely locked and held by thrusting such member into the frame or casing of the device where it causes the locking means to function immediately.

A further object is to provide releasing means whereby the locking means is retracted and the connector member either ejected or left free to be withdrawn.

To the above ends, the invention consists in the novel construction, combination, and arrangement herein fully described, shown and claimed.

In the accompanying drawings—

Figure 1 is a front face view of the device;

Fig. 2 is a rear view thereof;

Fig. 3 is a central longitudinal section through the same;

The releasable connector, in the illustrated embodiment thereof, comprises a frame or casing 5 of box-like formation having attaching lugs 6 to receive fasteners for securing the same to any kind of support such as a wall, post or manger. The frame 5 embodies a slot 7 forming the entrance to a guideway 8 lying between parallel guiding lugs or extensions 9 within the casing. The guideway 8 is designed to admit the connector member 10 which may consist of a ring or terminal link of a chain, cable or rope used for tethering or other purposes.

A locking bolt 11 slidable in guideways within the casing 5 is movable across the guideway 8 to engage and release the member 10, and is retracted and normally retained in non-functioning position by a spring 12 encircling the bolt and arranged between a pin or shoulder 13 on the bolt and a fixed part of the casing 5, such as one of the lugs 9.

One end of the bolt 11 is rounded as at 14 for cooperation with the correspondingly rounded cam face 15 of one arm of a bolt-operating lever 16 of bell crank type, said lever being fulcrumed at 17, the shorter arm working against the bolt 11, and the longer arm lying in the path of the member 10, so as to be actuated by said member as the latter is pushed through the guideway 8. As the lever 16 is acted on by the inward thrust of the member 10, the lever in turn acts on the bolt 11, forcing the latter into locking engagement with the member 10, as shown in Fig. 3.

When the lever 16 reaches the position shown in Fig. 3, it is caught and held by a keeper 18, pivotally mounted at 19, and yieldingly sustained in engagement with the extremity of the lever 16 by means of a spring 20. The keeper is shown as constituting the armature of an electro-magnet 21, within the casing 5. Upon energizing the magnet 21, the armature keeper 18 is moved out of engagement with the lever 16, tripping the latter and permitting the spring 12 to expand. This causes the bolt 11 to be quickly retracted and further causes the longer arm of the lever 16 to swing forward and strike the connector member 10, driving the latter out of the guideway 8. The lugs 9 are formed with notches 22 deep enough to receive the longer arm of the lever 16 and permit the same to strike against the member 10 to eject the latter from the casing.

The keeper 18 may be manually operated to release the connector member 10 by means of a push rod 23 attached at one end to the keeper and passing through a hole in wall 95 of the casing 5 where it is provided with push button or head 24. A spring 25, inside of the casing 5, engages a shoulder on the rod 23 and normally holds the head 24 in a projecting position as shown in Fig. 3.

By means of the construction above described it will be seen that the release operation may be effected either electrically or mechanically.

What I claim is:

1. A releasable connector embodying a casing having an opening therein, a connector member insertable into said opening, a movable bolt adapted to engage and release said connector member, a bolt-operating lever having a portion thereof in the path of said connector member, means for

retaining said lever in bolt-thrusting position, and means for retracting the bolt and causing said lever to strike and eject the connector member.

5. 2. A releasable connector embodying a frame having a guideway, a connector member insertable in said guideway and adapted to be engaged by a bolt, a bolt movable across said guideway to engage and release said connector member, a bolt-operating lever having a portion thereof in the path of said connector member, means for retaining said lever in bolt-thrusting position, and yieldable means for retracting the bolt and causing said lever to strike and eject the connector member.

3. An electric lock comprising a suitably housed electro-magnet and cooperating locking mechanism, including a tilting armature adjacent said magnet, said housing having a slot therein and a ring inserted through said slot, a sliding bolt projecting through said ring for holding it in said slot, a lever pivotally supported within said housing and held normally in a fixed position by said armature, said lever having an arm adapted in its fixed position to hold said bolt in locked engagement with said ring and another arm overlying said slot, a spring tending to cause said bolt to recede and release said ring, and means for throwing and releasing said tilting armature out of engagement with said lever, said spring being adapted to throw said lever into contact with said ring and eject it from said slot when the lever is released.

4. In combination, a casing having an opening through one side thereof, a ring inserted in said opening, a sliding bolt with-

in said casing adapted to be inserted through said ring for locking the same to said casing, a lever fulcrumed on a fixture within said casing having an arm normally pressing against and holding said bolt in locked engagement with said ring and another arm overlying said opening, releasable means for holding said lever normally in locked position, means for causing said releasable means to release said locking lever, and a spring acting on said bolt against the pressure of said lever releasing said ring when said lever is released; said spring being adapted to force said bolt against said lever and cause the long arm thereof to strike said ring and eject it from said slot when the lever is released.

5. An electro-mechanical lock comprising a casing having an oblong slot therein, a ring inserted through said slot, a sliding bolt normally projecting through said ring for securing it to said casing, a spring acting on said bolt to release said ring, a lever acting on said bolt against the force of said spring so as to hold it in locked engagement with said ring, said lever having an arm overlying said slot, releasable means for locking said lever with said bolt and ring in locked position, and independent electrically and manually actuated means for unlocking said lever being adapted to force said bolt against said lever and cause the long arm thereof to strike said ring and force it out of said slot when the lever is released.

In testimony whereof I have affixed my 75 signature.

EDWARD DEATRICK.
